REFRIGERATOR

Pauline E. Garth, 3114 E. 63rd St., Kansas City, Mo.

Filed Oct. 9, 1959, Ser. No. 57,868

Term of patent 14 years

(Cl. D67—3)

Fig. 1

Fig. 2

Fig. 1 is a perspective view of a refrigerator, showing my new design and illustrating one of the drawers thereof in open position; and

Fig. 2 is a side elevational view of the refrigerator shown in Fig. 1.

The rear of the refrigerator is substantially plain.

The printed matter shown in broken lines is for illustrative purposes only.

I claim:

The ornamental design for a refrigerator, as shown and described.
